BUCKLE

Joseph Shaulson, Providence, R. I.

Application June 22, 1940, Serial No. 341,824

1 Claim. (Cl. 24—200)

My present invention relates to the buckle art, and more particularly to a buckle construction which can be attached without threading or sewing.

5 The principal object of the present invention is to provide a buckle construction which can be readily attached to a tape or garter without the necessity of threading the same through the buckle or of sewing.

10 Another object of the present invention is to provide a buckle construction in which the tape or garter attachment may be readily removed from the buckle.

15 A further object of the present invention is to provide a buckle construction which will permit the ready adjustment of the tape without the necessity of removing the stitching or other attaching means thereon.

20 Another object of the present invention is to provide a buckle construction which can readily be applied to various types of buckles, hooks, garters, and the like.

25 With the above and other objects and advantageous features in view, my invention consists of a novel arrangement of parts more fully disclosed in the detailed description following, in conjunction with the accompanying drawings, and more specifically defined in the claim appended hereto.

30 In the drawings:

Fig. 1 is a front elevation of a simple buckle embodying my invention;

Fig. 2 is a front elevation of a double type of buckle embodying my invention;

35 Fig. 3 is a front elevation of a lingerie hook embodying my invention;

Fig. 4 is a front elevation of another type of hook embodying my invention;

40 Fig. 5 is a front elevation of the double buckle shown in Fig. 2 with a tape threaded therethrough;

Fig. 6 is a front elevation of a triple buckle embodying my invention;

45 Fig. 7 is a section taken along line 7—7 on Fig. 5;

Fig. 8 is a perspective view of a man's garter embodying my invention;

Fig. 9 is a perspective view of another form of 50 men's garter embodying my invention;

Fig. 10 is a perspective view of the buckle and hook shown in Fig. 4 with a tape threaded therethrough;

Fig. 11 is a front elevation of a garter buckle embodying my invention; and

Fig. 12 is a section taken along line 12—12 on Fig. 11.

In the manufacture of women's wear such as lingerie, brassières, garters, etc., it has been found desirable by the wearer to remove the 5 buckles from the garment when washing and ironing. The present invention is designed to provide a buckle construction which can readily be applied to various forms of lingerie buckles, garters, and the like, and which is easily attached 10 to the garment without sewing and is readily removable and replaceable by the wearer without the necessity of stitching or stapling.

Referring to the drawings illustrating my invention, Fig. 1 illustrates a construction embodying my invention in a simple type of buckle. The buckle 20 is provided at one end with a conventional loop portion 21 for permanently attaching to a garment as by sewing or stapling. The other end of the buckle comprises a detachable portion 20 15 having parallel side bars 23 and 24 with their ends extending towards each other as at 25 leaving a space or gap 26. Spaced from the main body portion of the buckle, the side bars 23 and 24 are provided with integral bar portions 27 25 and 28 extending in alignment towards each other and having their ends spaced as at 29. Between the bar portions 27 and 28 and the end 25 is an integral solid bar 30 extending between the bar portions 23 and 24. 30

In the construction shown in Fig. 2, the simple loop portion 21 in Fig. 1 is replaced by the demountable portion at the other end of the buckle to form a double buckle, both ends of which can be readily removed from the tape. In 35 this construction, side bars 31 and 32 are provided with a plurality of spaced parallel bar portions 33, 34, 35 and 36 extending towards each other and spaced in the center portion thereof to form two spaced broken parallel bars adjacent 40 the center of the buckle. On either side of the portions 33 to 36 inclusive and spaced therefrom are integral solid bar portions 37 and 38; the ends of the side bars 31 and 32 being bent towards each other in spaced relation to form open 45 end portions 39 and 40.

The method of attaching a demountable tape to the forms shown in Figs. 1 or 2 may be readily seen in Figs. 5, 7, and 8 to 10 inclusive. Referring to Figs. 5 and 7, which illustrate a tape at- 50 attached to the form of buckle shown in Fig. 2, the tape 41 is folded to form a loop 42 which is manually slipped over one of the split bar portions 43 on the buckle 44. The double strand of tape is then passed over the solid bar portion 45

and beneath the end portion 46 through the gap between the end portion. In this position, the pull on the tape frictionally locks the tape to the buckle without the necessity of any sewing or 5 stitching. To remove the tape it is merely necessary to slip the double tape portion from between the end portion 46 and then slide the loop out of the split bar portion 43. If it is necessary to adjust the length of the tape, the upper strand is 10 slipped out from beneath the end portions 46 and the tape can then be pulled for adjustment in any direction. Returning the upper strand portion to between the bar portion 46 locks the tape in adjusted position.

15 It can thus be readily seen that by utilizing the construction illustrated a tape or lingerie strap can be readily attached to the buckle without sewing or threading; it can be readily adjusted without the necessity of removing stitches or 20 other locking means; and that the buckle can be readily removed from the tape and replaced thereon for the purpose of washing or ironing the strap.

In the construction shown in Fig. 3, the buckle 25 47 is illustrated as provided with the locking portion 48 heretofore described and having an integral bar portion 49 which forms a hook in the plane of the buckle. In Fig. 4, the buckle 50 is provided with the locking portion 51 and a hook portion 52 outside the plane of the buckle. The 30 various types of hook portions with the locking member are of great utility in different types of lingerie and brassière tape constructions. However, other uses may be found, such as in garter 35 constructions.

For example, in the construction shown in Fig. 6, the buckle is provided with three lock members, a lower lock member 53 and two upper lock members 54 and 55 aligned at right angles to the 40 lower lock member 53. In utilizing such a construction for a garter, the aligned lock member can be used to retain a tape at right angles to the plane of the buckle, as in a man's garter, and the lower lock member 53 can be utilized to lock a vertically disposed tape at the end of which there may be a conventional garter attaching means.

In Fig. 8, the lock buckle of the present invention is shown with a man's garter, wherein the buckle 56 is of the type shown in Fig. 4. The buckle 56 is provided with a hook portion 57 and the garter 58 is locked into the buckle portion 59 which constitutes the present invention. The other end of the tape 58 is locked into a garter 60 comprising a lower garter portion 61 to which 55 the stocking can be attached, and an integral upper portion 62 which comprises substantially the buckle shown in Fig. 1 in a horizontal position. The tape 58 is locked to the lock portion of the buckle 63, and the hook portion 57 of the buckle 56 can be readily hooked into the loop portion 64 to close the garter.

Fig. 9 illustrates the use of the construction shown in Fig. 3 in a garter arrangement. This construction permits the use of only one buckle member 65 having a lower garter attaching portion 66 and an upper portion 67 integral therewith. By placing the integral hook bar portion 68 in an upright position, one end of the tape 69 may be locked into the lock portion and the other

end of the tape 70 may be slipped over the bar portion 68 in closing the garter.

Figs. 11 and 12 illustrate the lock portion attached to a garter buckle in which the operative portions of the garter buckle normally lie within the plane of the body; the upper lock portion 71 being provided with an integral depending portion 72 which comprises two side bars 73 terminating in ends 74 bent inwardly towards each other to form a gap portion 75. Intermediate 10 the side bar portion is an integral horizontal bar portion 76 having a friction detent 77 for holding the stocking. Between the upper lock portion 71 and the lower portion 72 is an integral bar portion 77^a to which a loop member 78 is 15 rotatably hung so as to depend between the side bar portion. In attaching a stocking to this construction, an edge of the stocking is pulled up by the wearer and threaded through the depending loop portion 78 which can be readily pushed out 20 from the plane of the garter for this purpose. The end of the stocking is then passed into the gap 75 and the edge of the stocking is also passed therebetween thus firmly locking the stocking to the garter. This type of locking action is similar 25 to that of the garter shown in Figs. 8 and 9 and is more particularly described in my copending application entitled Hose fastener and the like, Serial No. 341,822, filed June 22, 1940.

As can readily be seen from the foregoing construction, I have provided a buckle attaching means which is simple in construction and can be readily blanked out in a single piece from sheet stock. The construction of the present invention permits the attachment of a garter, hook, 35 buckle, or the like to a tape, lingerie strap, or any other article without the necessity of sewing, stapling or other outside attaching means. Furthermore, the present construction permits the ready removal of the buckle by the wearer for the purposes of washing or cleaning and also permits a ready adjustment as to length of the tape without the necessity of removing stitching or 40 stapling.

While I have described certain specific embodiments of my invention and I have illustrated the same as applied to garters, straps, and the like, it is obvious that changes in the size and shape and relative arrangement of the parts and its application to various devices may be made without departing from the spirit and the scope of the invention as defined in the appended claim.

I claim:

A buckle comprising an integral frame having top, bottom, and side bars, an intermediate bar portion spaced from said top bar and parallel thereto, said intermediate bar portion comprising aligned bars extending from each side bar towards each other and having spaced ends, and a second intermediate bar portion spaced from and parallel to said first intermediate bar portion, said frame bottom bar comprising two aligned bars extending towards each other and having their ends spaced, the top portion of said buckle comprising means for attaching said buckle to a strap, said bars all being in the same plane.

JOSEPH SHAULSON.
